BUS DOOR SAFETY LOCK BAR

Julius E. Zaitz, Hammond, Ind.

Application January 13, 1936, Serial No. 58,978

1. Claim. (Cl. 268—3)

The present invention relates to a lock bar, and more particularly, a lock especially adapted for doors of a motor vehicle such as a bus or the like.

5 One of the objects of the present invention, is to provide a lock bar of the class described, which will prevent the closing of the door or doors of a bus while passengers are loading and unloading thereby preventing injury to the passengers.

10 A still further important object of the invention, is to provide a device of the character described, in which the door, when in a closed position, cannot be opened, until the device is operated by the operator of the bus.

15 A still further important object of the invention, is to provide in a device of the character described, novel means for preventing actuation of the lock bar, when the door is open, and the operator of the bus is outside of the bus.

20 A still further important object of the invention, will be found to reside in the novel safety latch construction, permitting of the door to be positively locked in closed position, or in open position, thereby preventing the door from causing injury to the passengers.

In the accompanying drawings wherein corresponding parts are designated by similar reference numerals:—

25 Figure 1 is a front elevational view of the device showing the position of the same for maintaining the door in a closed position.

Figure 2 is a top plan view of Figure 1.

30 Figure 3 is a vertical sectional view of Figure 2 taken on line 3—3 thereof looking in the direction of the arrows.

Figure 4 is a top plan view of Figure 3.

35 Figure 5 is a view similar to Figure 3, showing the position of the latch when the handle is actuated, to release the same from the catch box.

Figure 6 is a front elevational view of the device for locking the door in open position.

Figure 7 is a top plan view of Figure 6.

40 Figure 8 is a fragmentary top plan view, showing the position of the latch, with respect to the door of the lock box for preventing the door from being locked in closed position, when the operator is not in the bus.

45 Figure 9 is a fragmentary front elevational view of the latching mechanism and the lock box showing the position of the latch, with respect to the door for preventing the door from being locked in closed position.

50 Figure 10 is a perspective view of the lock box or catch.

In the accompanying drawings wherein for the purpose of illustration there is shown a preferred embodiment of the invention, the reference numeral 12 generally designates, the front portion of a passenger motor vehicle such as a bus or the like, to which there is in the usual manner pivotally mounted a door 14. The door 14, in busses of this character, are for the most part generally located opposite the seat of the driver, and are adapted through some means, to be 10 manually opened and closed by the operator.

5 It has been found, that many of the devices, now in use, for effecting the opening and closing of the doors of the bus, are not provided, with safety means for preventing the unintentional 15 opening and closing of the door and consequently serious injury is caused to the passengers by the accidental opening of the same.

In the present invention, to the front portion 12 of the bus, there is secured, by means of bolts or the like a bracket 16 on which there is pivotally mounted for movement in a horizontal plane an arm 18. The free end of the arm, is apertured and through the medium of the pin 20 has pivotally mounted thereon a bar 22 which bar has 25 its free end bifurcated as at 24 and pivotally mounted to the door 14 for effecting an opening and closing of the same, through the medium of the bracket 26. As clearly illustrated in the drawings, the bifurcated end 24 of the bar 22 is pivotally mounted to the bracket 26 through the medium of the pin connection 28.

30 To the lock bar 22 at a position, within reach, and accessible to the operator of the bus, there is secured a latch box 30, the latch box being 35 provided with a depending handle 32. It will thus be seen that the operator, through the medium of the handle 32 upon an outward pushing or an inward pulling may effect the opening or closing of the door 14 of the bus.

40 Referring now to Figure 3, it will be seen that within the latch box 30 adjacent the upper portion of the handle 32, there is pivotally mounted an actuating lever 36, which actuating lever as clearly illustrated, is normally urged away from 45 the handle 32, through the medium of the spring 38. One end of the spring 36 is securely fastened to the handle 32 through the medium of a screw 40, the free end of the spring abutting the lower inner portion of the lever 36. As clearly illustrated in the drawings, the handle 32 is provided on its upper end with an integral inwardly extending bifurcated portion 46, in which the upper portion of the handle 36 is pivotally mounted through the medium of the removable pin 48. 50 55

The upper portion of the lever 36 is provided with an integral laterally extending projection 50, the free end, in the outer position of the handle 36, abutting the inner end of the latch box 30 as clearly shown in Figure 3. It is to be noted in this connection, that the projection 50 is movable in the longitudinally extending slot 54 of the latch box 30, the free end of the projection 50 and the inner end of the slot is provided with rectangular shaped dovetail connections 56. Within the latch box 30, there is pivotally mounted centrally thereof through the medium of the pin 58 a latch 60 the free end of which projects through an opening in the end of the box 30, for suitable engagement and connection with a catching mechanism to be hereinafter more fully described.

The latch bar 60, has its innermost free end connected to the projection 50, through the medium of the link 62, to the end, that upon inward movement of the lever 36, as clearly illustrated in Figure 5 the latch bar 60 is rotated, causing the free outer end thereof to be raised vertically, and upon release of the lever 36, the latch 60 moves through the medium of the springs 37 and 38 to its downward catching position.

Referring now, to Figure 6, it will be seen when the handle is pulled to its innermost position, effecting an opening of the door, to the front portion 12 of the motor vehicle opposite the latch box when in that position, there is securely fastened, to the front portion 12 a bracket 66 having on the outer free end thereof, an integral catch box 68. The outer free end 70 of the catch box 68 extends upwardly, and is adapted to cooperate with the free outer end of the latch, for securely fastening the latch thereto and maintaining the lock bar in position. It will thus be seen, that when the door is in the position illustrated in Figure 6, that is in open position, the same may be securely locked in that position, through the engagement of the latch bar 60 with its cooperating catch box 68. Upon inward movement of the lever 36, the latch bar may be raised thus disengaging the same from the latch box to the end that the operator may push the handle outwardly to the position illustrated in Figures 1 and 2, for effecting a closing of the door. Securely fastened to the front portion 12 of the bus, in a position opposite the latch box 30 when in this position is a similar bracket 62 and catch box 68 for locking the door in closed position. The catch box 68 cooperating with the latch bar 60 when in this position, is, however, provided with a door 74, as illustrated in Figures

3 and 5. Normally this door is in its raised position as illustrated in Figures 3 and 5, however, when the operator desires to leave the bus with the door in closed position the door 74 is closed as illustrated in Figure 9 to the end, that the free end of the latch bar 60 cannot engage the upward projection 70 of the catch box 68 to effect a locking of the door while he is out of the bus.

It will thus be seen, that the door by virtue of the novel construction of the latch box, and its cooperating catch may be locked in either closed or open position, and when so desired, the operator may either lock the door in open position, or upon closing the door 74 of the catch box or catch move the door to closed position without fear of being locked out of the bus.

While there is shown for the purpose of illustration, a preferred embodiment of the invention, it is to be specifically understood, that it is capable of various changes and modifications without departing from the spirit and scope thereof, and it is intended therefore, that only such limitations shall be imposed thereon as are indicated in the prior art or in the appended claims.

What is claimed is:—

A door actuating device for busses of the class described comprising a pivotally mounted door, an arm pivotally mounted on the interior of said bus for swinging movement in a horizontal plane, a bar having one end pivotally connected to the free end of said arm and the other end pivotally connected to said door whereby upon movement of said bar in one direction the door is moved to closed position and in the other direction to open position, a depending handle on said bar disposed intermediate the ends thereof, a latch box adjacent said bar, a pivotally mounted latch bar in said box, a lever pivotally mounted adjacent said handle for actuating said latch bar, a pair of spaced U-shaped catch members disposed in said bus, said latch bar being cooperable with one or the other of said catch members for maintaining and locking the door in the closed or open position thereof, said catch members cooperable with said latch bar for maintaining the door in closed position, being provided with a hinged mounted door in its lower position preventing the engagement of the latch bar with said catch members whereby said handle may be moved to a position to close said bus door without the engagement of the latch bar with said catch member.

JULIUS E. ZAITZ.
